UNITED STATES PATENT OFFICE.

WALTER S. PAYNE, OF UNIVERSITY PLACE, NEBRASKA.

ELECTRIC-MOTOR-DRIVEN SPRING HAMMER.

Application filed July 11, 1923. Serial No. 650,781.

This invention relates to an improved electric motor driven spring hammer, and is a simplification and improvement with respect to the device shown and described in my Patent 1,356,556, dated Oct. 26th, 1920.

One object of this invention is to simplify and reduce the cost of manufacturing a machine of this character by eliminating the hammer-lock and hammer-case-lock as well as other parts which formed elements of the above mentioned device (of Patent No. 1,356,556).

Another object is to make the hammer-plunger work freer in the hammer-case than it works in other devices of this character.

Another object is to double the number of blows or hammer-strokes, as compared with the number produced by a given number of revolutions of the cam-carrying shaft that constitutes part of the hammer-driving mechanism.

Another object is to provide a simple and comparatively inexpensive hammer-extension or weight which adds impact to the hammer.

Another object is to provide an improved, yet comparatively simple spring-pressed means for automatically and securely locking the hammer-case and cam-crosshead in their screw-threaded engagement with the cam-case.

Other objects and advantages will be pointed out or implied in the following details of description, in connection with the accompanying drawings in which:—

Fig. 1 is a somewhat diagrammatic view which shows the interior of the main shell (which may be of any number of united parts) and the elements contained therein.

Fig. 2 is a view of the combined cam-case and hammer-case, its intermediate part being broken out.

Fig. 3 is a view of the combined hammer-guide and cam-case.

Fig. 4 is a view of the hammer and its extension or weight.

Fig. 5 is a view showing three different views of the double cam-device in the same position.

Fig. 6 is a view of the gearing which operatively connects the motor to the cam-shaft.

Within the main shell, an electric motor is indicated at 5, and its driven shaft 6 carries a gear wheel 7 which meshes with

a gear wheel 8 whose shaft or axle also carries a gear wheel 9, the latter meshing with a gear wheel 10 on a shaft or axle 11. The shaft 11 carries a cam-member 12 which is the first element thus far named which is different from the electro-mechanical driving mechanism shown in my prior patent, above mentioned.

The rotary cam member 12 has its complement in a non-rotary cam-member 13 which is secured against rotation in a combined hammer-guide and cam-case or cam-guiding member 14 and reciprocates in the latter. A hammer-case or tool-carrying member 15 is provided with slots or recesses 15^a. A hammer 16 is in the hammer-case and has arms or legs 17 which slide in slots 14^a of the member 14, and also in the slots 15^a of member 15 which are alined with the slots 14^a. These arms have lugs 17^a that fit in notches 13^a of the non-rotary cam and are held in these notches by the pressure of a spring 18 whose rear end presses against the cam-case while its front end presses against the hammer in the relation for shooting the hammer forward at each half revolution of the cam-member 12. It should of course be understood that the shaft 11 extends through the cam 13, the latter being in the form of a hollow cylinder. The cam 12 is also in the form of a hollow cylinder, but its axial bore is fitted around the forward end of the shaft 11 and secured thereto with a tapering diametral pin or other securing means. As the cam-member 12 rotates, its cam-faces slide on those of the cam 13, and this pushes the latter rearward during the travel of cam 12's highest or rearmost points to the highest or foremost points of the cam 13; but when these highest points have passed one another, the spring 18 shoots the hammer forward, and the cams then intermesh with one another as is shown in the drawing. This shooting forward of the hammer occurs twice in each revolution of the cam-member 12, which has two diametrically opposite cam-faces, the cam 13 also having such opposite cam faces. Each time the hammer is shot forward, its front end strikes the shank 19 of the riveting tool, chisel or other tool.

For the purpose of adding impact to the hammer, without affecting the diameter thereof, and without affecting the efficiency

of the spring 18, I provide a rearward extension 20 which may be of soft steel or wrought iron and has a screw-threaded connection with the rear end of the hardened steel hammer-head. This weight 20 is relatively long and of smaller diameter than the interior of the spring 18, and if it were of hardened steel, or an integrally formed part of the hammer's head, it would be likely to break off in consequence of the vibrations caused by the rapidly repeated impacts. The main body of the member 20 is cylindrical and has a slot across its rear end for receiving a screw-driver whereby to screw or unscrew it.

The cam-case is provided with a diametral bore 21 in which is carried two locking plungers or pins 22, and between them is a spring 23 which presses them outward through slots 17^b into diametrically opposite holes of an internally threaded shell or hollow cylinder 24 whose front end abuts against an annular shoulder 25 of the outer casing or hammer-case-housing, and the rear end of the member 24 abuts against a ball-bearing 26 which comes into use when the machine is used for drilling or boring as described in the prior patent above named. The pins 22 extend through the recesses 15^a and thence into diametrically disposed openings 24^a of the shell 24, and when thus fitted while the pins are engaged with the shell 24, the members 14, 15 and 24 are immovably locked with relation to one another; and to unlock them, it is necessary to press the pins 22 inward so that the members 15 and 24 are free from engagement therewith. These pins can be held depressed by any appropriate means while these parts are being assembled, and when they are released, the spring 23 automatically operates to cause the pins to lock them in the assembled relation. Each of these pins 22 has a shoulder to limit its outward movement and avoid bearing against the outer shell.

The parts not specifically described in this specification are shown and described in one

or more of my prior patents, especially the one above referred to.

Although the present drawings show slots 17^b through the legs 17, it should be understood that the pins 22 may extend between the legs, instead of through them, by making slight changes of construction and arrangement whereby these pins may extend at right angles to the position shown in Figure 1.

It is not intended to limit this invention to the exact details of construction and arrangement here shown, but changes may be made within the scope of the inventive ideas as implied and claimed.

What I claim as my invention is:

1. In a machine of the character described, the combination of a cam-guiding member having an externally screw-threaded part 65 and a reduced cylindrical part forming a seat for a compression spring and also having a radial bore which latter opens through said cylindrical part, a tool-carrying member having a cylindrical inner surface receiving said cylindrical part of the first said member, said tool-carrying member also having a screw-threaded outer surface and a recess adjacent to the latter, a hollow cylinder having an internally threaded part to 75 mesh with the screw-threads of the first said member and tool-carrying member for uniting them, and a spring-pressed pin in said radial bore and normally pressed by its spring so that it extends through said recess into engagement, with said hollow cylinder for locking the cam-guiding member and tool-carrying member and hollow cylinder in a fixed screw-threaded relation to one another.

2. The structure defined by claim 1, said pin having a reduced outer end portion and having an abutment, said hollow cylinder having an opening to receive the reduced end portion, said abutment normally engaging the wall of the opening to prevent the pin from passing out through said opening.

In testimony whereof I affix my signature.
WALTER S. PAYNE.
